United States Patent Office

Des. 174,980

Patented June 21, 1955

174,980

COFFEE MAKER OR SIMILAR ARTICLE

Robert D. Budlong, Skokie, Ill., assignor to Cory Corporation, a corporation of Delaware

Application November 15, 1954, Serial No. 33,096

Term of patent 14 years

(Cl. D44—26)

To all whom it may concern:

Be it known that I, Robert D. Budlong, a citizen of the United States, residing at Skokie, in the county of Cook and State of Illinois, have invented a new, original, and ornamental Design for a Coffee Maker or Similar Article, of which the following is a specification, reference being had to the accompanying drawing, forming part hereof.

In the drawing:

Fig. 1 is a side elevational view of a coffee maker or similar article showing my new design.

Fig. 2 is a front elevational view thereof.

Fig. 3 is a rear elevational view thereof.

Fig. 4 is a top plan view thereof.

I claim:

The ornamental design for a coffee maker or similar article, as shown.
